UNITED STATES PATENT OFFICE.

JACOB KOHN, OF NEW YORK, N. Y.

LOCK.

1,299,195.

Specification of Letters Patent.

Patented Apr. 1, 1919.

Application filed November 29, 1916. Serial No. 134,019.

To all whom it may concern:

Be it known that I, JACOB KOHN, a citizen of the United States, and resident of the borough of Manhattan, city, county, and 5 State of New York, have invented certain new and useful Improvements in Locks, of which the following is a specification.

My invention relates to locks for doors and the like and has for its object to provide 10 a simple and easily operated construction having a maximum of efficiency and whereby doors or the like may be securely held against forcing or other unintentional opening. My improvements will be fully 15 described hereinafter and the features of novelty will be pointed out in the appended claims.

In the accompanying drawings, which illustrate examples of my invention, Figure 20 1 is a face view of a lock with parts broken away and in section; Fig. 2 is a sectional view on line 2—2 of Fig. 3; Fig. 3 is a sectional view on the line 3—3 of Fig. 1; Fig. 4 is a view similar to Fig. 2 but showing the 25 parts in another position; Fig. 5 is a sectional view on the line 5—5 of Fig. 3; Fig. 6 is a plan view with the door and part of the casing in section; Fig. 7 is a sectional view on the line 7—7 of Fig. 1; Fig. 8 is an 30 edge view; Fig. 9 is an elevation of another form of my improved lock and Fig. 10 is a horizontal section thereof on the line 10—10 of Fig. 9.

As shown by way of example in Figs. 1 to 35 8 inclusive the lock comprises a casing 11 preferably constructed of metal and having a back or cover 12 whereby the interior of said casing may be exposed, said back 12 being detachably secured in position for instance by means of screws 13 arranged to 40 screw into internally screw-threaded posts or the like 14 located interiorly of said casing 11. A plate or slide 15 is located in said casing 11 and is formed with flanges 16 and 45 17 extending into contact with the fixed or front wall 11^a of said casing, the flange 17 being located in engagement with the one end wall 11^b thereof as shown in Fig. 6. The said plate or slide 15 is further provided 50 with a projection 18 which contacts with the other end wall 11^c and carries an upright rod 19 extending between two guide lugs 20 rigidly fixed in said casing, a coil spring 21 surrounding said rod 19 and having its one 55 end in engagement with the projection 18 and its other end abutting against said lugs 20 or against a washer 22 interposed between said spring and said lugs as shown in Figs. 2, 3 and 5. In addition to the above the plate or slide 15 is constructed at its upper edge 60 with flanges 22 and 24 extending therefrom in opposite directions preferably into contact respectively with the front wall 11^a and the cover 12 of the casing. With the arrangement as described the plate or slide 15 is 65 vertically movable in the casing 11 and is guided in its vertical movements by the flange 17 and projection 18 in coöperation with the end walls 11^b and 11^c and the rod 19 in coöperation with the lugs 20. The 70 slide 15 is preferably further maintained in and guided in a substantially fixed vertical path by means of the flanges 16, 23 and 24 in coöperation with the front wall 11^a and cover 12 as will be readily apparent, and is maintained in and returned to its initial position by means of the spring 21 and another spring 15^a coiled about a post 11^d in the casing 11 and having its one end in engagement 75 with the top wall of said casing and its other end resting upon the combined flanges 23—24. At its one end the plate 15 is continued in the form of a bolt 25 which extends beyond the casing 11 through a recess 11^e formed in the end wall 11^b and is provided at its free end 80 with a transverse member forming a hook 26 as clearly shown in Fig. 6. In the illustrated example the locking mechanism further includes an arm 27 rigidly connected with and projecting radially outward from 85 a stem 28, and located beneath the flange 23 of the slide 15; the stem 28 is rotatably mounted in and extends through the wall 11^a of the casing 11 and either forms an integral part of or is connected with an actuating knob 29 located exteriorly of said casing upon said wall 11^a as shown in Fig. 3.

The arm 27 is preferably formed with a continuing projection 30 carrying a pin 31 against which one end of a spring 32 90 abuts, the opposite end portion of said spring being held between two lugs 33 in the casing 11 as shown in Fig. 5. A second arm 34 is located beneath the flange 24 of the slide 15 and projects radially outward from 95 a sleeve 35 rotatably mounted in the cover 12, suitable means being provided for preventing an axial movement of said sleeve 35 relatively to the cover 12 as shown in Fig. 3. The said sleeve is formed with an axial 100

110

opening 36 of angular cross-section the purpose of which will appear more clearly hereinafter. A suitable stop 37 located on the wall 11^a of the casing 11 is provided for arresting the movement of said arm 27 in one direction, in order to prevent an unintentional operation of the parts and a disarrangement thereof.

The lock further includes a lever 38 having its one end pivotally connected with a pin 39 in the casing 11, said lever 38 extending adjacent to one face of the slide 15 and having its free end formed with a notch 40 adapted to receive a lug 41 carried by said slide 15 as shown in Fig. 1. The lever 38 is controlled by means of a spring 42 and under its influence is always pressed in a direction toward said lug 41 whereby a proper coöperation between the latter and the notch 40 is always assured. The lever 38 is formed with an extension 43 which at its free end is provided with a finger 44 extending transversely through an aperture 45 in the slide 15 and of sufficient dimensions to permit the parts to operate in the intended manner without interference. The finger 44 is constructed with an inclined surface 46 so arranged as to be common to the free ends of the arms 27 and 34 which are preferably rounded as shown in the drawings. In the normal position of the locking mechanism as shown in Fig. 1, which is the operative position, the coöperation of the lug 41 and notch 40 will, through the medium of the lever 38 prevent the slide 15 and bolt 25 from being raised to an inoperative position.

A second lever 47 has its one end pivotally connected with the pin 39 and depends therefrom adjacent to the other face of the slide 15 so that the latter is located between the two levers 38 and 47 as is clearly shown in the drawings. The lever 47 is provided at an intermediate point with a notch 48 which is adapted to coöperate with a lug 49 carried by the slide 15 to maintain the latter and with it the bolt 25 in a raised inoperative position, the notch 48 being somewhat larger than the lug 49 for the purpose to be more fully described hereinafter. Said lever 47 is also controlled by a spring 50 in such a manner that the lever is always pressed in a direction toward the lug 49 whereby the desired engagement of the notch 48 and lug 49 automatically takes place at the proper time. At its lower end the lever 47 carries a dog 51 pivotally connected at 52 and being free to pivotally move in one direction relatively to the lever 47 but having its relative pivotal movement in the opposite direction arrested by a stop 53 formed on said lever at the proper point. Any suitable means may be provided for maintaining the dog 51 in and for returning it to its normal position, as for instance a leaf spring 54 having its one end secured to

the dog and its other end in engagement with a projection 55 carried by the lever 47 as shown in Figs. 2 and 4. The lower portion of the dog 51 comprises a nose 51^a which projects beyond the lower end of the lever 47 and normally extends into the path of a head 56 carried by a rod 57. The latter is slidably mounted in a stationary guide 58 in the casing 11 and is connected with or forms part of a plunger 59 slidably mounted in the end wall 11^b of said casing and projecting exteriorly beyond the same as shown in Figs. 2, 4 and 5, said plunger preferably having its outer end beveled as indicated at 60. A coil spring 61 surrounds the rod 57 with its one end in engagement with the guide 58 and its other end in contact with the plunger 59 and always tends to return said plunger to the normal position shown in Figs. 2, 4 and 5.

85

The bolt 25 is arranged to coöperate with a keeper 62 having a vertically open recess 63 for the accommodation of said bolt and being further formed with a shoulder 64 behind which the hook 26 is located in the operative position of the locking mechanism. In addition to the above said keeper is provided with a cam surface 62^a adapted to coöperate with the plunger 59 in a manner and for the purpose to be more fully set forth hereinafter. In the illustrated example the casing 11 is shown as secured by means of screws 65 upon the inside surface of an inwardly swinging door 66, while the keeper 62 is suitably connected with the door 101 casing 67 in proper coöperative relation to the lock for instance by means of screws 68. When arranged as above described the lock or more specifically the slide 15 and with it the bolt 25 may be operated from the inside 101 by means of the actuating knob 29. The manipulation of the locking mechanism from the outside is usually accomplished by means of key actuated mechanism which as illustrated in the present instance includes a key plate 69 located upon the outside surface of the door 66 and a tumbler barrel 70 extending from said key plate into an aperture 71 extending transversely through said door. Any suitable means may be employed for securing the key 69 and tumbler barrel 70 upon the door, as for instance screws 72 extending through a plate 73 located at the inner end of the aperture 71 into screw threaded engagement with ears 74 formed on the tumbler barrel 70 as shown in Fig. 3. The latter, in the illustrated example, is operatively connected with the locking mechanism by means of a connecting rod 75 of angular cross section which fits with the angular axial 12 opening 36 of the sleeve 35 and which if desired may extend through the same as shown in Fig. 3. In this latter case the slide 15 is preferably formed with a slot 76 into which the inwardly projecting end of the rod 75 13

may extend and whereby interference with the intended operation of the parts is avoided.

When the locking mechanism is in its operative position and the bolt 25 is located in the recess 63 of the keeper 62 the door 66 is firmly locked against any movement on its hinges, while at the same time through the coöperation of the hook 26 and shoulder 64 10 it is absolutely impossible to bring about any material movement of the door edge *a* away from the edge *b* of the casing 67. It is thus absolutely impossible for instance to jimmy the door or to break the operative connection 15 between the bolt 25 and the keeper 62 as is clearly shown in Fig. 6.

If the door 66 is to be legitimately opened from the inside the actuating knob 29 is rotated upon its axis and thus causes a corresponding movement of the stem 28 whereby the arm 27 is swung in the arc of a circle, the direction of rotation being such as to cause the free, preferably rounded end of said arm to bear against the under side of 25 the flange 23. During this movement of the arm 27 and prior to its contact with the flange 23 the free end of the arm engages the inclined surface 46 of the finger 44 and exerts a camming action thereon. Through 30 the medium of the extension 43 this brings about a pivotal movement of the lever 38 in a direction to disengage the notch 40 from the lug 41 so that the resistance to an upward movement of the slide 15 which is normally 35 exerted by said lever 38 is removed. As the actuation of the arm 27 by means of the knob 29 is continued the free end of said arm will finally exert an upward pressure upon the flange 23 and will thus raise the slide 15 and with it the bolt 25 and hook 26 40 against the tension of the springs 15^a and 21. The upward movement of the slide 15 continues until the notch 48 of the second lever 47 snaps over the lug 49 as shown in Fig. 4 45 at which time the bolt 25 and hook 26 have been moved completely out of the recess 63 and from behind the shoulder 64 of the keeper 62. The coöperation of the notch 48 and lug 49, through the medium of the lever 50 47, serves to maintain the locking mechanism in its inoperative position so that the door 66 may be freely opened without difficulty. The actuation of the knob 29 as described is ordinarily continued only until 55 the bolt 25 is actually disengaged from the keeper, the arm 27 at this stage occupying a position inclined slightly to the left in Fig. 5 and at a distance from the stop 37. If the described operation of the locking mechanism is not carried beyond the above indicated point, said mechanism will be automatically returned to its operative position in which the bolt 25 is located in the recess 63 of the keeper 62 as soon as the door is 60 closed. This is accomplished in the follow-

ing manner and by means of the following devices:—As the door 66 is moved toward its closed position the beveled end 60 of the plunger 59 will finally engage the cam surface 62^a of the keeper 62 whereby the plunger will be forced inwardly against the tension of the spring 61. As this happens the rod 57 and head 56 will be similarly moved and the latter will engage the projecting nose 51^a of the dog 51 and will exert a pressure thereon toward the left in Fig. 4 thus forcing said dog into contact with the projection 53 whereby said dog 51 and lever 47 in effect become a rigid unit. The result of this operation is that the lever 47 is swung 75 upon its pivot 39 in a direction to disengage the notch 48 from the lug 49. As soon as this happens the slide 15 is free to again move downwardly and under the influence of the springs 15^a and 21 is returned to its 80 initial operative position. The cam surface 62^a and plunger 59 are so correlated that this return of the slide 15 does not take place until the bolt 25 is in registry with the recess 63 so that the bolt 25 is thus automatically 85 moved back into the recess 63 and the hook 26 behind the shoulder 64 of the keeper 62 whereby the door is again securely locked.

If it is desired to prevent this snapping of the lock or in other words to maintain 90 the door 66 in an unlocked condition, the actuating knob 29 is given an extra turn to bring the arm 27 against the stop 37 as shown in Fig. 5. In this position of the parts the arm 27 is located beneath the 100 flange 23 in a position perpendicular thereto; thus even if the plunger 59 and its connected parts are actuated as the door is closed and the lever 47 is pivotally moved to disengage the notch 48 and lug 49 as previously described, this will have no effect and the slide 15 will be maintained in its raised position by the arm 27. Owing to its position relatively to the flange 23 the tension of the springs 15^a and 21 will have 105 no effect to move the arm 27 or the slide 15 as will be obvious from an inspection of Fig. 5; the bolt 25 and hook 26 will thus be held in an inoperative position with respect to the keeper 62 so that the door 66 may be 110 freely opened and closed without difficulty as long as the parts are in the described positions. Owing to the fact that the notch 48 is slightly larger than the lug 49 these elements do not interfere with the slight 115 additional raising of the slide 15 as the arm 27 is moved into contact with the stop 37. When it is again desired to bring the locking mechanism to an operative condition the actuating knob 29 is actuated in a reverse 120 direction to move the arm 27 away from the stop 37 whereupon the springs 15^a and 21 will return the parts to the normal operative positions. As soon as the arm 27 has been 125 moved out of the perpendicular the spring 130

32 will return it to its normal position so that only a slight initial movement of the arm 27 through the medium of the knob 29 is required to bring about the described 5 operation. If at any time the head 56 is moved beyond the nose 51^a of the dog 51 to the left in Figs. 2 and 4, for instance when the door is closed and the plunger 59 is pressed inwardly, the said dog will inter- 10 pose no resistance to the return of the head 56, rod 57 and plunger 59 to their normal positions under the influence of the spring 57, owing to the fact that said dog 51 is free to move relatively to the lever 47 to- 15 ward the right in said Figs. 2 and 4. In other words as the head 56 engages the nose 51^a in a return movement the dog will simply be swung upon its pivot 52 without performing any function.

20 To open the door 66 from the outside the proper key 77 is inserted into the key hole of the key plate 69 and rotated in the usual manner, which causes a rotation of the connecting rod 75 and a similar movement of 25 the sleeve 35. As the latter is thus rotated about its axis the arm 34 will be moved in the arc of a circle, the direction of movement being such as to cause the free end of said arm 34 to travel toward the flange 24.

30 During this movement of said arm its free end will first engage and exert a pressure upon the inclined surface 46 of the finger 44 whereby the lever 38 is pivotally moved to disengage the notch 40 and lug 41 35 and release the slide 15 in the same way as hereinbefore described. As the movement of the arm 34 is continued it will finally bear against the flange 24 from below and will raise the slide 15 and bolt 25 and bring 40 about an operation of the coöperating parts corresponding to the one brought about by the actuation of the arm 27 as hereinbefore set forth. The automatic return of the parts to normal position as the door is closed 45 is accomplished in the same way as explained previously, or in other words the operation of the locking mechanism is the same whether the arm 27 is operated by the knob 29 from the inside or the arm 34 is 50 actuated by means of the key 77 from the outside. The slide 15 and its connected parts are also automatically returned to their normal operative positions through the medium of the plunger 59, it being understood that 55 the locking mechanism is not intended to be fixed in a raised, inoperative position from the outside although provision for bringing this about may be made if desired.

In the form shown in Figs. 9 and 10 I 60 have shown the lock provided with a different form of bolt and keeper, adapted especially for locking doors which open outwardly, the casing 11 being connected to the inside surface of the door 66^a as before 65 while the keeper 62^a is secured to the door

casing 67^a in proper coöperative location. In the illustrated example the bolt 25^a is provided with a transverse number 26^a which is continued in the form of a member 26^b extending toward the lock in a direction substantially parallel with the bolt 25^a the members 26^a and 26^b forming a hook as shown in Fig. 10. In the form now being described the keeper 62^b is provided with an upright member 64^a corresponding in effect to the shoulder 64 and spaced from the keeper to form a vertically open recess 63^a which in the present instance is also open at the ends as shown in Fig. 10.

When the bolt 25^a is in its operative position the member 26^a will be located in the recess 63^a while the member 26^b will extend behind the upright member 64^a of the keeper, or in the other words the hook formed by the members 26^a and 26^b will be in coöperative engagement with the shoulder formed by the upright member 64^a. With the parts in this position it is obvious that the member 26^b in coöperation with the upright member 64^a will prevent the door 66^a 90 from being opened outwardly and thus securely lock it in its closed position while the coöperation of the member 26^a with said member 64^a will prevent any substantial movement of the edge *a*¹ of the door 66^a 95 away from the edge *b*¹ of the door casing 67^a. In this form it is thus also absolutely impossible for instance to jimmy the door or to break the operative connection between the bolt 25^a and the keeper 62^b, as will be 100 clear from an inspection of Fig. 10. The mechanism for and method of operating the bolt 25^a and its connected parts may be the same as described with respect to Figs. 1 to 8 inclusive.

It will be seen that in all of its forms my improved lock is extremely efficient in action and is proof against any tampering whereby an illegitimate entrance through the door 66 or 66^a may be effected. My improved 110 lock may also be effectively used in connection with sliding or rolling doors as will be apparent from the drawings. The construction is extremely simple so that my improved lock, while it possesses a very high 115 degree of efficiency, is not likely to become disarranged in use and may be produced at a relatively low cost.

Various changes in the specific forms shown and described may be made within 120 the scope of the claims without departing from the spirit of my invention.

I claim:

1. A lock comprising a casing, a slide movable rectilinearly up and down therein, 125 a bolt carried by said slide so as to always project exteriorly of said casing, means movably connected with said casing for locking said slide against vertical movement, manually operated means for operating said 130

locking means to release said slide and for vertically moving the latter independently of said locking means and key actuated means operating independently of said 5 manually operated means to move said locking means to an inoperative position and to vertically move said slide.

2. A lock comprising a casing, a slide movable rectilinearly up and down therein, 10 a bolt carried by said slide so as to always project exteriorly of said casing, a device pivotally mounted on said casing for locking said slide against upward movement, a plurality of means operating independently 15 of each other for moving said locking device to release said slide and for raising the latter, a second device independent of said first device and pivotally mounted on said casing for maintaining said slide in its 20 raised position, means for moving said second device to release said slide and means for moving said slide downwardly, the upward and downward movements of said slide being independent of said locking devices.

25 3. A lock comprising a casing, a slide movable rectilinearly up and down therein, a bolt carried by said slide so as to always project exteriorly of said casing, a first lever pivotally mounted in said casing, coöperating 30 means on said lever and slide whereby the latter is locked against upward movement, a plurality of independently operated means for moving said lever to release said slide and raise it, a second lever pivotally 35 mounted in said casing, coöperating means on said second lever and slide whereby the latter is held in a raised position, a plunger for moving said second lever to release said slide and a spring for moving said slide 40 downwardly.

4. A lock comprising a casing, a slide vertically movable therein, a bolt carried by said slide, horizontal flanges extending in opposite directions from said slide, a pair 45 of movable arms adapted to engage said flanges from below to raise said slide, a knob for actuating one of said arms, key-actuated mechanism for actuating the other arm, a first lever pivoted in said casing, coöperating 50 means on said lever and slide whereby the latter is locked against upward movement, a device carried by said lever adapted to be engaged by both of said arms whereby said lever is moved to release said slide 55 prior to its upward movement, a second lever pivotally mounted in said casing, coöperating means on said second lever and slide whereby the latter is held in a raised position, a dog pivotally mounted upon said 60 lever and freely movable relatively thereto in one direction but locked against movement in the opposite direction, a plunger adapted to engage said dog and move said second lever to release said slide, and a 65 spring for moving said slide downwardly.

5. A lock comprising a casing, a slide vertically movable therein, a bolt carried by said slide, means for raising said slide, means for temporarily maintaining said slide in its raised position, means for moving said maintaining means to release said slide and means for moving said slide downwardly, said slide raising means being movable to a position to fix said slide in its raised position independently of said maintaining means. 70

6. The combination of a door casing, a keeper connected therewith, a door hinged in said casing, a lock casing carried by said door, a bolt vertically movable in said casing and arranged to coöperate with said keeper to lock the door, means for raising said bolt to disconnect it from said keeper, means mounted in said casing independently 80 of said bolt for maintaining it in its raised position, a plunger mounted in said casing independently of said bolt for moving said maintaining means to release said bolt, means connected with said keeper for actuating said plunger as the door is closed and 85 means for moving said bolt downwardly.

7. The combination of a door casing, a keeper connected therewith, a door hinged in said casing, a lock casing carried by said door, a bolt vertically movable in said casing and arranged to coöperate with said keeper to lock the door, means for raising said bolt to disconnect it from said keeper, means for maintaining said bolt in its raised 95 position, a plunger for moving said maintaining means to release said bolt, means connected with said keeper for actuating said plunger as the door is closed and means for moving said bolt downwardly, said bolt raising means being movable to a position 100 to fix said bolt in its raised position independently of said maintaining means. 105

8. The combination of a casing, locking mechanism therein, a slide forming part of said locking mechanism movable thereby rectilinearly up and down in said casing, a bolt carried by said slide and movable therewith, a transverse member at the free end of said bolt and a second member at the end of said transverse member extending substantially 110 parallel to said bolt. 115

9. The combination of a casing, locking mechanism therein, a slide forming part of said locking mechanism movable thereby rectilinearly up and down in said casing, a substantially L-shaped bolt carried by said slide and movable therewith, and a keeper having a vertically open L-shaped recess adapted to receive said bolt. 120

10. The combination of a casing, locking 125 mechanism therein, a substantially U-shaped bolt connected with said mechanism and comprising substantially parallel members and a transverse member connecting said parallel members, said bolt being vertically 130

movable by said mechanism in a linear direction, and a keeper having an upright member adapted to extend behind the transverse member of the bolt and into the space 5 between the substantially parallel members thereof.

11. A lock comprising a casing, a bolt movable therein to and from an operative position, means for locking said bolt in one 10 of its positions, movable means for actuating said locking means to release said bolt and a dog operatively combined with said locking means and providing a rigid abutment against which said movable means im- 15 pacts in its operative movement, said dog being movable relatively to said locking means to permit said movable means to move in a return direction independently of and without actuating said locking means.
12. A lock comprising a casing, a bolt 20 vertically movable therein, a lever for maintaining said bolt in its raised position, a dog pivotally mounted on said lever and locked against relative movement thereto in one di- 25 rection and freely movable thereon in the opposite direction, a plunger, and means operatively connected with said plunger and arranged to engage said dog whereby said lever is actuated to release said bolt as said plunger is moved inwardly, said dog being 30 moved on its pivot relatively to said lever by said plunger whereby the latter is permitted to move in a return direction independently of said lever.
13. A lock comprising a casing, a bolt slide- 35 able rectilinearly up and down therein and always projecting exteriorly beyond said casing, means independent of said bolt for locking it in its operative position, a pro- 40 jection operatively connected with said locking means and having an inclined surface and means in said casing arranged to engage said inclined surface whereby said locking means is actuated to release said bolt.
14. A lock comprising a casing, a bolt mov- 45 able rectilinearly up and down therein and always projecting exteriorly beyond said casing, a lever pivotally connected with the casing for locking said bolt in its operative 50 position, a projection carried by said lever and having an inclined surface and key controlled and manually controlled arms in said casing common to said projection and each arranged to engage said inclined surface to 55 actuate said lever and release said bolt.
15. The combination of a door casing, a keeper connected therewith, a door movably mounted in said casing, a lock casing carried by said door, a bolt movable rectilinearly 60 up and down in said casing and always pro- jecting exteriorly beyond the same and co-

operating with said keeper to lock the door, means for moving said bolt to disconnect it from said keeper, means for maintaining said bolt in its disconnected position, a plunger mounted in said casing independently of said bolt for actuating said maintaining means to release said bolt and a cam member connected with said keeper for actuating said plunger as the door is closed.

16. A lock comprising a casing, a pair of levers pivotally mounted in said casing, a slide movable rectilinearly up and down in said casing independently of said levers, a bolt carried by said slide and always projecting exteriorly beyond the casing, co-operating means on said levers and slide whereby the latter is locked respectively in its raised and lowered positions, means for actuating one of said levers to release said slide for movement in one direction and independent means for actuating the other lever to release said slide for movement in the opposite direction.

17. The combination of a casing, locking mechanism therein, a slide forming part of said mechanism and movable thereby rectilinearly up and down in said casing, a bolt carried by said slide and movable therewith, said bolt having a portion located exteriorly of said casing in all positions of said bolt, a projection located exteriorly of said casing at the free end of said bolt and extending transversely to the direction of movement of said bolt and slide and means whereby said locking mechanism is actuated.

18. The combination of a casing, a slide vertically movable therein, a bolt carried by said slide, a pair of flanges projecting from said slide in opposite directions transverse to its plane of movement, pivoted arms located on opposite sides of said slide and movable beneath and into engagement with said flanges whereby said slide and bolt are raised and independent means for individually actuating each arm.

19. The combination of a casing, a slide vertically movable therein, a bolt carried by said slide, a flange projecting from said slide in a direction transverse to its plane of movement, a lever for locking said slide against upward movement, an arm located in proximity to a major surface of said slide and arranged to actuate said lever to release said slide and movable beneath and into engagement with said flange whereby said slide and bolt are raised and means for actuating said arm.

In testimony whereof I have hereunto set my hand.

JACOB KOHN.
